UNITED STATES PATENT OFFICE.

WILLIAM BARTHOLOMEW, OF CHICAGO, ILLINOIS, ASSIGNOR TO TROY LAUNDRY MACHINERY COMPANY, LIMITED, OF CHICAGO, ILLINOIS, A CORPORATION OF NEW YORK.

GUDGEON.

1,095,783.

Specification of Letters Patent.

Patented May 5, 1914.

Original application filed May 28, 1913, Serial No. 770,460. Divided and this application filed August 14, 1913. Serial No. 784,743.

To all whom it may concern:

Be it known that I, WILLIAM BARTHOLOMEW, a citizen of the United States, residing at Chicago, in the county of Cook and State 5 of Illinois, have invented certain new and useful Improvements in Gudgeons, of which the following is a specification, reference being had therein to the accompanying drawing.

10 This invention relates to certain new and useful improvements in trunnion construction for knock-down washing cylinders and comprises a division of my application for knock-down renewable washing cylinder,
15 filed May 28, 1913, Serial Number 770,460; the object being to provide novel means for connecting the trunnion plate to the head, whereby the same can be easily and quickly attached or detached; said members having
20 coöperating portions in order to prevent the same from moving after being placed in position.

Another and further object of the invention is to provide a trunnion plate with conical projections which extend into sockets formed in the head which are provided with threaded bores to receive a machine screw which extends through the projection so as to force the same into the sockets and set 25 surely lock the same therein.

Another object of the invention is to provide a washing cylinder which is exceedingly simple and cheap in construction; the head being formed with a hub having spokes carrying the ribs and staves of the washing cylinder and to which the trunnion is detachably connected.

Other and further objects and advantages of the invention will be hereinafter set forth and the novel features thereof defined by the appended claims.

In the drawings—Figure 1, is a perspective of a washing cylinder showing the arrangement of the trunnion plate upon the head; Fig. 2, is a vertical longitudinal section through a portion of the cylinder showing the manner of fastening the trunnion plate in position; Fig. 3, is a detail plan view of a portion of the hub of a washing cylinder head, showing the sockets; and Fig. 4, is a detail section through one of the sockets and projections of the trunnion plate showing the bolt in position for securing the projections within the sockets.

Like numerals of reference refer to like parts in the several figures of the drawings. 55

In the drawing, 1 indicates a washing cylinder which is provided with head members carrying the staves as clearly set forth in the original application; said head members being provided with hub portions 2 from which radiate spokes 3 preferably channeled and provided with rib sockets 4 at their ends; said spokes being connected together by a rim 5 upon which the staves are mounted and the rim between one pair of spokes is enlarged as shown at 6 provided with a central inset portion forming one member of the hoop tightener as fully described in my former application; the adjacent side portion of the enlarged portion forming a support for the hoop 7. The hub portion is provided with spaced sockets 8 preferably cylindrical in shape having a central threaded bore formed in their bottoms for the purpose later described. 75

The skeleton trunnion plate 10 of substantially the same diameter as the hub, is arranged against the outer face thereof and is formed with spaced conical projections 11 adapted to fit within the sockets 8 of the hub and said projections are provided with bores 12 through which machines bolts 13 are adapted to pass into the threaded bores 9 of the sockets so as to draw the projections 11 into the sockets in such a manner that a wedging effect will be obtained in order to prevent the same from moving in any direction, whereby the trunnion plate will be fixed firmly to the head in such a manner that the same can be easily and quickly attached or detached.

It will be seen that by providing the trunnion plate with these projections which extend into the sockets of the head, that the strain on the bolts 13 is relieved; the bolts serving the purpose of fastening the projections into the sockets and as the strain is axially, the bolts are not subjected to any stress and, therefore, the connection is such that an exceedingly strong and durable means is provided for connecting the trunnion plate to the head. The trunnion plate 10 is provided with a central hub portion 14 in which the trunnion 15 is mounted by any suitable means.

The construction of washing cylinder including the ribs, staves and manner of fas-

tening the same in position upon the rim of the head is clearly shown in the original application and the manner of placing the head plates in order to form a tight joint 5 between the staves, ribs and head is also clearly described and illustrated in the original application and it is not necessary to go into detail in connection with this invention.

From the foregoing description, it will 10 be seen that I have provided a trunnion construction for a renewable knock-down washing cylinder which is so constructed that when placed in position, it will be securely fastened upon the head and when power is 15 applied to one of the trunnions, the cylinder will be rotated in such a manner as to prevent any danger of the same being twisted off.

I claim:

1. A trunnion connection, comprising a 20 member having a hub portion provided with spaced circular sockets having central threaded bores, a trunnion plate arranged

upon said hub provided with spaced apertured conical projections extending into said sockets and bolts extending through the 25 bores of said projections into the threaded bores of said sockets for securing said trunnion plate in position thereon.

2. As a new article of manufacture, a head member having a hub portion provided 30 with spaced cylindrical sockets having centrally arranged threaded bores, a trunnion plate having spaced conical apertured projections extending into said sockets, and threaded members passing through the apertures of said projections working in the threaded bores of said sockets for securing said head member and plate together.

In testimony whereof I affix my signature in presence of two witnesses.

WILLIAM BARTHOLOMEW.

Witnesses:
